UNITED STATES PATENT OFFICE.

CHARLES ALBERT DIES, OF CHICAGO, ILLINOIS.

HAIRPIN.

1,377,408.

Specification of Letters Patent. Patented May 10, 1921.

Application filed June 23, 1916. Serial No. 105,472.

To all whom it may concern:

Be it known that I, CHARLES A. DIES, a citizen of the United States, residing at Chicago, in the county of Cook and State 5 of Illinois, have invented certain new and useful Improvements in Hairpins, of which the following is a description.

My invention relates to that class of devices used in dressing ladies' hair and commonly known as hair pins.

The object of my invention is to provide a device of the kind described which when inserted in the hair will retain its position until it is desired to remove it and also one 15 by means of which the hair may be secured and firmly retained in its desired position and so obviate the inconvenience and annoyance caused by the falling out of the pins and consequent derangement of the 20 hair.

To this end my invention consists in the novel construction, arrangement and combination of parts herein shown and described, and more particularly pointed out in the 25 claims.

In the accompanying drawings wherein like or similar reference characters indicate like or corresponding parts:

Figure 1 is a side elevation of my improved hair pin.

Fig. 2 is an edge elevation of the same.

Fig. 3 is a section taken substantially on line 3—3 of Fig. 1.

Fig. 4 is a side elevation of a slightly 35 modified form of my improvement.

Fig. 5 is a similar view of another modified form.

In the form shown in Figs. 1, 2 and 3 my improvement comprises a member 1 formed 40 of wire or other suitable material, bent substantially at its center to form a U shaped pin with arms of substantially uniform length. As shown a portion 2 of the arms at the closed end of the pin are substantially parallel and lie in a common plane 45 while the next adjacent portion of the arms are bent to form a helix about a common center 3 and diverge from each other toward the free ends of the arms to the point 50 5, the next adjacent portion 6 of the arms while continuing the helical curve about the center line 3 converge regularly toward the free ends of the arms while the end portion 8 of the arms still continuing the helical 55 curve again diverges to the end of the arm so that in twisting the pin into the hair the

divergent portion 8 in passing through the hair tends to force the free ends of the arms apart so that the parts 6 will assume a position substantially parallel to each other 60 when in service and resiliently engage the hair positioned between the arms to hold the pin and the engaged hair in position.

When thus constructed it is obviously desirable that the bending action when in service should occur as far as possible in the parts 4 of the pin which being of considerable length permits a free resilient movement of the parts 6 and 8 without permanently distorting the pin. To insure this action 70 the member 1 is preferably flattened as shown near the closed end of the pin substantially parallel to the common plane of the arms at this point, or, in some cases where the member 1 is formed of wire of 75 substantially uniform size, the member is tapered in thickness slightly toward the closed end of the pin thus giving the part 2 of the arms a slightly tapering form laterally as shown. 80

In the preferred construction also a laterally projecting bead 9 is provided on both sides of the pin at the outer margin of its closed end preferably extending entirely across the end of the pin thus further stiffening this portion of the member and provide a convenient grip for the fingers in inserting or removing the pin from the hair. In this form also the pitch of the helical 85 curve is reduced slightly toward the free 90 end of the arms to still further increase the holding effect of the pin and prevent its disengagement from the hair when in service.

In the form shown in Fig. 4 my improved hair pin is formed in all respects substantially the same as shown in Figs. 1 to 3 with the single exception that in this form the section 11 of the arms corresponding to the section 6 in the form hereinbefore described the arms are substantially parallel instead 100 of converging. In this form when in service the arms are slightly divergent or spread toward their free ends and while forming an excellent device for securing the hair in position does not retain its place in the hair as 105 satisfactorily as the form hereinbefore described.

In the form shown in Fig. 5 my improved hair pin is constructed substantially the same in all respects as the form shown in Figs. 110 1 to 3 with the single exception that the pitch of the helical curve in the form shown in

Fig. 5 remains constant throughout its entire length instead of decreasing toward the free end of the arms. The general utility and holding power of this form of my device is very nearly, if not quite as satisfactory as the form shown in Figs. 1 to 3.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. A hair-pin comprising a U shaped member having arms of substantially uniform length, each curved helically about a common central axis, said arms gradually approaching each other to a point adjacent their free ends and thereafter diverging slightly to their extremities, said member being flattened at the closed end of said pin

parallel to the common plane of said arms and having a laterally projecting bead on both sides of the pin at the outer margin thereof.

2. A hair-pin comprising a U shaped member having arms of substantially uniform length, each curved helically about a common central axis, said arms gradually approaching each other to a point adjacent their free ends and thereafter diverging slightly to their extremities, said member being flattened near the closed end of said pin parallel to the common plane of said arms and having a laterally projecting bead at the outer margin of the closed end of the pin.

In testimony whereof I have hereunto signed my name in the presence of two subscribing witnesses.

CHARLES ALBERT DIES.
